nesota

Application July 31, 1944, Serial No. 547,500

8 Claims. (Cl. 222—193)

1

Our invention relates to powder sprayers and has for an object to provide a powder sprayer which will be effective to spray powder regardless of the position in which the device is held.

Another object of the invention resides in providing in one form of the invention a powder sprayer having a case and a removable receptacle or cartridge within the same and in which the powder is contained and which may be easily mounted in the sprayer.

A feature of the invention resides in providing a receptacle for the powder in which the powder may be sold and which may be used in the sprayer without material alteration or change.

An object of the invention resides in providing a powder sprayer in which the receptacle virtually floats within the case.

An object of the invention resides in providing a powder sprayer in which an annular air passageway is provided within the case extending about the exterior of the powder receptacle.

A still further object of the invention resides in constructing said receptacle with laterally extending outlet openings communicating with said annular passageways at the ends of the receptacle.

A feature of the invention resides in providing air pumping means at one end of said passageway and discharge means at the other end of said passageway.

An object of the invention resides in providing means for restricting the flow of air entering said air passageway to cause the same to expand upon entering the passageway and to cause suction in said receptacle through the outlet openings at the inlet end of the annular passageway.

A still further object of the invention resides in providing an expansion chamber at the outlet end of the annular passageway and into which the air leaving the annular passageway is directed, whereby suction is caused in the receptacle through the lateral openings at the outlet end of said annular passageway.

Another object of the invention resides in providing a construction whereby the receptacle within the interior of the device in one form of the invention may be readily filled with powder after the device has been fabricated.

Other objects of the invention reside in the novel combination and arrangement of parts and in the details of construction hereinafter illustrated and/or described.

In the drawings:

Fig. 1 is an end view of a powder sprayer illustrating an embodiment of our invention.

2

Fig. 2 is a longitudinal sectional view taken on line 2—2 of Fig. 1.

Fig. 3 is a view similar to Fig. 1 with the powder sprayer inverted and the parts in partly extended position.

Fig. 4 is a cross-sectional view taken on line 4—4 of Fig. 2.

Fig. 5 is a cross-sectional view taken on line 5—5 of Fig. 2.

10 Fig. 6 is a cross-sectional view taken on line 6—6 of Fig. 2.

Fig. 7 is a cross-sectional view taken on line 7—7 of Fig. 2.

Fig. 8 is a plan view similar to Fig. 1 of another form of the invention.

Fig. 9 is an elevational sectional view taken on line 9—9 of Fig. 8.

Fig. 10 is a perspective view of the container or cartridge removed from the case.

20 Fig. 11 is a cross-sectional view taken on line 11—11 of Fig. 9.

Fig. 12 is another cross-sectional view taken on line 12—12 of Fig. 9.

In the use of powder sprayers in which the air is conducted from one end of the sprayer to the other, considerable difficulty is encountered where a small air passageway is provided. Such passageway usually appreciably reduces the capacity of the device and when constructed of small dimensions conducts too little air and frequently becomes clogged. The instant invention provides a device in which clogging is prevented and in which a sufficient volume of air can be conducted through the passageway.

35 The form of our invention shown in Figs. 1 to 7 comprises a receptacle or cartridge indicated in its entirety by the reference numeral 10 and which is disposed within a case or container 11. Associated with this container is a pumping cylinder 12, by means of which air is forced into the device to create suction therein and draw powder into the air stream for discharge through the discharge outlet of the container. These various parts will now be described in detail.

40 The container 11 consists of a sleeve 13 of tubular material, such as paper which has a closure 14 at its lower end and a closure 15 at its upper end. The closure 14 is preferably constructed of metal and is formed with a flange 16 which is crimped to the lower end of the sleeve 13 and which lies substantially within the confines of the outer surface of said sleeve, so as to provide a flush constructed for coaction with the pumping means, as will be presently more fully described. This closure, as shown in Fig. 6, has

a central opening 17 in the same which is covered with a sheet of fabric 18. This fabric is impervious to the powder within the container 11 but will allow air to pass readily through the same.

The other closure 15 for the opposite end of the container 11 consists of a tubular member 50 which encircles the sleeve 13 and fits tightly about the same. This tubular member has secured to the end of it a metal ring 19 which is constructed with a flange 21 crimped to the outer end of said tubular member. The closure 15 is applied to the end of the sleeve 13 and when in position, closes the upper end of the container 11. The ring 19 has an opening 22 in the same surrounded by a lip 20 and through which access may be had to the interior of the device. The opening 22 is adapted to be closed by a cap 23 which has an end wall 31 and a flange 30 issuing outwardly therefrom. The flange 30 engages the lip 20 of ring 19 and forms a fluid-tight connection therewith. The tubular member 50 in the assembly of the parts is glued or otherwise secured to the sleeve 13, so that the same becomes permanently attached thereto.

The receptacle 10 consists of a tubular body portion 24 open at its upper and lower ends. This body portion is of slightly smaller dimensions than the internal diameter of the sleeve 13, so as to form therebetween an annular passageway 25 extending throughout the length of the receptacle 10. The receptacle 10 further includes two end members 26 and 27 which overlie the ends of the tubular body portion 24. These end members are detached from the body portion 24 and the ends of said body portion are constructed so that laterally extending openings 28 are formed between the end member 26 and the tubular body portion 24 and similar openings 29 between the other end of the tubular body portion 24 and the end member 27. These openings communicate with the ends of the passageway 25.

The end member 26 of receptacle 10 is spaced from the ring 19 of closure 15 to provide a chamber 32 at the upper end of the device. The end member 27 is similarly spaced from closure 14 of the container 11 to provide a pressure chamber 33 at the opposite end of the device. The end member 26 fits snugly within the interior of the sleeve 13, excepting at certain portions about the periphery thereof where the same is formed with circumferentially extending openings 64. These openings bring the passageway 25 into communication with the chamber 32. The end member 27 is similarly constructed and fits snugly within the sleeve 13 excepting where the same is formed at its periphery with openings 35 bringing the air chamber 33 into communication with the other end of the annular passageway.

The end wall 31 of cap 23 has a discharge opening 34 in the center of the same which communicates with a radial passageway 36 lying between the end wall 31 of cap 23 and the end member 26 of receptacle 10. This passageway communicates with the chamber 32 and conducts the air from the annular passageway 25 to the discharge opening 34. To maintain the said passageway 36 open at all times, the end wall 31 of cap 23 is constructed with a number of bosses 37 which are pressed inwardly therefrom and which hold the adjoining parts in spaced relation.

The pumping cylinder 12 consists of a tubular member 41 constructed of paper which has a closure 42 secured to the outer end thereof. This

closure is preferably formed of metal and has a flange 43 crimped about the outer end of the said tubular member 41. The tubular member 41 and the closure 42 constitute a cylinder which, acting in conjunction with the container 11 which serves as a piston, provides a pressure chamber 40 in which air may be compressed when the said cylinder is moved toward the closure 14 of the container 11. The closure 42 has an air inlet 44 which is adapted to communicate with the chamber 40. Overlying the closure 42 is a valve indicated in its entirety at 45 in Fig. 7. This valve consists of a disk 46 constructed of paper or some similar material which is formed with a crescent shaped cut 47 dividing said disk into an annular portion 48 resting upon the closure 42, and a central portion 49. The said disc is further weakened along the line 51, so that the central portion serves as a valve flapper for controlling the flow of air through the inlet 44. When the cylinder 12 is drawn outwardly, valve 49 opens to permit entry of air into the pressure chamber 40. Upon reversal of movement, the valve flapper 49 closes the inlet 44 and the air is forced into the air chamber 33 through the air passageway 17 in closure 14.

For the purpose of filling the interior of the receptacle 10 with the powder, a central opening 53 is formed in the upper end member 26. This opening is adapted to be closed by means of a cover 54 which is of dimensions smaller than those of the opening 22 in ring 19 and which is insertable into the device through said opening. The bosses 37 on the cap 23 are adapted to engage this cover and to hold the end member 26 away from the end wall 31 of cap 23, so as to maintain passageway 36 open. The cover 54 may be glued to the end member 26 or the same may be left loose, as desired. It will be noted that the diameter of the hole 53 is such that the cover 54 closes said hole, even in the event that said cover is shifted laterally until it engages the inner surface of the sleeve 13. Thus, the hole 53 is maintained closed at all times.

The tubular member 41 extends up to the tubular member 18 and the two may be temporarily held in position by means of a label, band or other readily fracturable wrapper, which extends about these parts and which may be secured thereto in the customary manner.

The method of assembling the device is as follows: The end member 27 is first inserted into the container 11 and then the tubular body portion 24 dropped in upon the same. Thereafter, the end member 26 is placed upon the tubular body portion 24 and the closure 15 applied. This closure is then glued or otherwise secured to the sleeve 13 and the parts are then permanently held in position. Since hole 22 in ring 19 is of lesser diameter than the diameter of the end member 26, the said end member remains within the container 11 and holds the other parts in position.

In filling the receptacle 10, the powder is inserted through the opening 22 in closure 15 and through the hole 53 in the end member 26. The cover 54 is next placed upon the end member 26 and the cap 23 applied. A piece of paper or similar material is preferably glued over the discharge outlet 34, whereupon the powder sprayer is completed and ready to be furnished to the user.

In the use of the invention, the label or other seal connecting the tubular member 41 to the tubular member 50 is first broken and the paper closing the discharge opening 34 either removed

or perforated. To operate the device, it is merely necessary to pump the cylinder 12 back and forth. This successively draws air into the pressure chamber 40, compresses the air and forces the same into the air chamber 33 from which it passes through the annular passageway 25 and into the chamber 32. The air, upon entering this chamber, passes through the passageway 36 and is discharged through the discharge outlet 34. As the air enters the annular passageway 25, it expands and causes a suction in the powder outlets 29 and/or 34 which draws powder into the passageway 25 and mixes the same with air. The powder-laden air is then directed through the passageway 36 and discharged from the discharge outlet 34. From the drawings, it will be seen that when the device is arranged in upright position, as shown in Fig. 2, that powder enters the annular passageway 25 through the lower openings 29. When, however, the device is inverted, as shown in Fig. 3, the powder enters the said annular passageway through the upper openings 28. It will also be readily comprehended that since the passageway 25 is annular, the device may be operated regardless of the position of the same, since powder can enter the passageway 25 from any locality about the circumference of the receptacle.

While we have referred to the powder as entering the passageway 25 through suction caused by the air passing through said passageway, it will be readily comprehended that a certain amount of powder sifts into the said passageway through the disturbance set up in the device by the manipulation of the pumping means and also by the action of gravity. The receptacle 10 fits freely within the container 11 and is moved during manipulation of the device. This keeps the passageway 25 clear and also assists in discharging powder into the same.

While the discharge outlets 28 and 29 have been shown in the drawings as of substantial proportions, it can readily be comprehended that these outlets can be made of proper dimensions to discharge the exact amount of powder desired. I have found in practice that with the construction of the parts of paper, the roughness of the parts when constructed in the ordinary manner, provides sufficient openings to permit the discharge of a sufficient amount of powder into the air stream.

The form of the invention shown in Figs. 9-12 is similar to that previously described. For this reason, the description of the similar parts will not be repeated, and the same reference numerals preceded by the digit "1" will be used to designate corresponding parts.

The container 111 is similar to the container 11, excepting that the sheet of fabric covering the opening 117 in the closure 114 of said container is omitted. Instead of the same, a disk of cardboard is employed which is shown in Fig. 11 and indicated by the reference numeral 61. This disk fits freely within the lowermost portion of the sleeve 113 and rests on a flange 62 extending upwardly from the closure 114 at the margin of the opening 117. The edges of the disk 61 are cut away to provide openings 63. By means of this construction, a valve is provided which permits passage of air through the opening 117 and into the interior of the container 111, but which prevents the flow of air in the opposite direction.

The tubular member 150, which is similar to the body 50 of the closure 15 in the other form

of the invention, is securely attached to the sleeve 113. Encircling the outer edge of this tubular member and the sleeve 113 is a ring 119 similar to ring 19 of the other form of the invention. This ring has a flange 121 crimped to the outer surface of the tubular member 150 and a flange 120 crimped to the inner surface of the sleeve 113. By means of this construction, the upper end of the container 111 is open for the reception of the receptacle 110 and the opening therein is substantially the same as the internal diameter of sleeve 113.

The receptacle 110 differs from the receptacle 10 in that the same is constructed with end members or caps 64 rigidly secured to the tubular body portion 124 of the same. These caps are formed of metal and are provided with internal flanges 65 and external flanges 66 which are crimped about the edges of the tube and hold 20 the said cap securely attached thereto. The caps 64 are each constructed with a raised portion 67 at the center of the same leaving an annular depression 68 extending about the said raised portion. The flanges 66 are pressed into the material of the tubular body portion 124, so that the receptacle 110 is smooth upon the exterior thereof. The caps 64 at both ends of the receptacle are identical, so that either end of the receptacle may be directed into the container in 30 applying the same thereto.

The open end of the container or case 111 is closed by means of a cap 123 which is identical with the cap 23, except that the cap 123 is of suitable dimensions to engage the flange 120 of 35 the ring 119. The raised portion 67 of the uppermost cap 64 of the receptacle 124 is adapted to engage the bosses 137 formed on the same to provide a passageway 136 from the chamber 132 to the discharge opening 134. The receptacle 124 is held in proper position by a compression coil spring 69 which is received within the depression 132 of the lowermost of the caps 164 and which engages the disk 61. This spring, in addition to holding the receptacle in position, 40 serves to maintain the disk 61 closed and thereby prevents leakage of powder out of the container 111.

At the upper ends of the tubular portion 124 of receptacle 110 are provided openings 71 which 50 communicate with the interior of the said receptacle and with the annular passageway 125 formed between the receptacle 110 and the container 113. These openings may be formed at the factory and covered by seals or other closures 55 adapted to be easily ruptured by the user when the device is desired for use. If desired, the said openings may be made entirely by the user and instructions merely printed upon the exterior of the tubular portion 124 of the receptacle indicating where the holes or openings are to be made. In either event, these openings are cleared prior 60 to the use of the device.

The pumping mechanism of this form of the invention is the same as that shown in Figs. 1-7.

With the form of the invention disclosed in 65 Figs. 8-12, the powder may be placed in the receptacle 110 at the factory and the said receptacle sold separately from the case and pump mechanism of the invention. When desired for use, the holes 71 are either formed or opened up 70 and the receptacle slid into the container 111.

The receptacle may be inserted with either end entering the container, since both ends are identical in construction. The said container then 75 rests upon the spring 69 which is expanded. Cap

123 is next applied and when forced into closing position, compresses the spring 69 which holds the parts in operating position. It will readily be comprehended that the cartridges or containers having the powder in them may be sold as refills and a single case and pumping mechanism used repeatedly.

The method of operation and of use of the invention shown in Figs. 8-12 is the same as that shown in Figs. 1-7.

The advantages of our invention are manifest. The parts are easily constructed and at a nominal expense. Assembly of the parts of the powder sprayer can be quickly and easily made. Since the air passageway is annular, danger of clogging is entirely prevented and the air passageway maintained open at all times. The receptacle for the powder virtually floats within the container of the invention and is moved about within the container, during use, so that any powder which may lodge within the annular passageway is constantly agitated and is positively ejected from the device by the air stream passing through the air passageway. The device operates in exactly the same manner whether one side of the device or the other is uppermost, or whether the device is held vertically, horizontally or tilted in either direction. The fabric member overlying the opening in the lower closure of the container in the one form of the invention prevents the powder from being discharged into the air pressure chamber and leaving from the wrong end of the device. In the one form of the invention, the powder may be packed in cartons at the factory and used as refills by the user.

Changes in the specific form of our invention, as herein described, may be made within the scope of what is claimed without departing from the spirit of our invention.

Having described our invention, what we claim as new and desire to protect by Letters Patent is:

1. In a powder sprayer, a receptacle comprising a tubular body portion and end members associated therewith, a sleeve surrounding said body portion and spaced therefrom to form an annular passageway extending about said receptacle, said receptacle having transverse outlet openings arranged circumferentially about said receptacle to communicate with said annular passageway at different localities therein, spaced circumferentially from one another, a closure for one end of said sleeve spaced from the corresponding end member of said receptacle at certain portions thereof and forming an air chamber therebetween communicating with said annular passageway, closure means for the other end of said sleeve spaced from said other member at portions thereof to form a transverse passageway, said second named closure means having a discharge opening therein communicating with said transverse passageway and means at the other end of said receptacle associated with said sleeve for forcing air through said annular passageway.

2. In a powder sprayer, a receptacle comprising a tubular body portion open at its ends, end members overlying both ends of said body portion and detached from said body portion at certain localities to provide laterally extending outlet openings at both ends of said receptacle, a sleeve surrounding said body portion and spaced therefrom to form an annular passageway extending about said receptacle, said outlet openings discharging laterally into said passageway, means at one end of said passageway associated

with said sleeve for forcing air through said passageway and discharge means at the other end of said passageway.

3. In a powder sprayer, a receptacle comprising a tubular body portion open at its ends, end members overlying the ends of said body portion and detached from said body portion at certain localities to provide laterally extending outlet openings at the ends of said receptacle, a sleeve surrounding said body portion and spaced therefrom to form an annular passageway extending about said receptacle, said outlet openings discharging laterally into said passageway, means at one end of said passageway associated with said sleeve for forcing air through said passageway, means for constricting the air entering the said passageway at the locality of one of said lateral openings to provide rapid expansion of the air into the annular passageway and suction in said lateral opening of the receptacle and discharge means at the other outlet end of said passageway.

4. In a powder sprayer, a receptacle comprising a tubular body portion open at its ends, end members overlying the ends of said body portion and detached from said body portion at certain localities to provide laterally extending outlet openings at the ends of said receptacle, a sleeve surrounding said body portion and spaced therefrom to form an annular passageway extending about said receptacle, said outlet opening discharging laterally into said passageway, means at one end of said passageway associated with said sleeve for forcing air through said passageway, means for constricting the air entering the said passageway at the locality of one of said lateral openings to provide rapid expansion of the air into the annular passageway and suction in said lateral opening of the receptacle and means forming an expansion chamber at the other end of said passageway and into which the same discharges, said expansion chamber producing suction within the receptacle through the other lateral opening and discharge means at the other end of the said sleeve and communicating with said expansion chamber.

5. In a powder sprayer, a receptacle comprising a tubular body portion and end members at the ends of the same, said tubular body portion having laterally extending outlet openings therein at both ends thereof, a sleeve surrounding said body portion and spaced therefrom to form an annular passageway extending about said receptacle, said outlet openings discharging laterally into said passageway, means at one end of said passageway for forcing air through said passageway, means for constricting the air entering the said passageway at the locality of one of said lateral openings to provide rapid expansion of the air into the annular passageway and suction in said lateral opening of the receptacle and discharge means at the other end of said passageway.

6. In a powder sprayer, a receptacle comprising a tubular body portion and end members at the ends of the same, said tubular body portion having laterally extending outlet openings therein at both ends thereof, a sleeve surrounding said body portion and spaced therefrom to form an annular passageway extending about said receptacle, said outlet openings discharging laterally into said passageway, means at one end of said passageway for forcing air through said passageway, means for constricting the air entering the said passageway at the locality of one of said lateral openings to provide rapid expan-

sion of the air into the annular passageway and suction in said lateral opening of the receptacle and means forming an expansion chamber at the other end of said passageway and into which the air from the annular passageway discharges, said expansion chamber producing suction within the receptacle through the other lateral opening and discharge means at the other end of the said sleeve and communicating with said expansion chamber.

7. In a powder sprayer, a tubular case having a circumferential wall and a closure closing one end of said case, a receptacle for powder within said case having a circumferential wall of lesser external diameter than the internal diameter of the circumferential wall of said case to form an annular passageway therebetween, an end member for said receptacle, means for spacing said end member from said closure to form an end chamber communicating with said annular passageway, said receptacle having a laterally extending opening discharging into said annular passageway, said closure having a discharge opening centrally located therein and communicating with said end chamber and pumping means for forcing air through said annular passageway.

8. In a powder sprayer, a receptacle comprising a tubular body portion and end members associated therewith and closing the same at its ends, a sleeve surrounding said body portion and spaced therefrom to form therebetween an annular pas-

sageway, outlet openings in said receptacle arranged circumferentially about said receptacle to communicate with said annular passageway at different localities therein spaced circumferentially from one another, means at one end of said annular passageway associated with said sleeve for forcing air through said passageway, and discharge means at the other end of said annular passageway including a chamber communicating with said annular passageway and receiving the discharge from any of said outlet openings.
